MOUTHPIECE

Henry P. Roberts, Brooklyn, N. Y., assignor to
 Dictaphone Corporation, Bridgeport, Conn., a
 corporation of New York

Application April 19, 1926, Serial No. 102,946
 Renewed July 16, 1932

10 Claims. (Cl. 181—21)

This invention relates to sound collectors, and more particularly to mouthpieces for dictating machines.

An object of this invention is to provide a mouthpiece or sound collector which is large enough to collect a major portion of the sounds emitted by the speaker or dictator while the mouthpiece is sufficiently far removed from the speaker's face to receive both the guttural and nasal sounds, and yet one which will not be excessively heavy.

Another object is to provide a mouthpiece or sound-collector which tends to eliminate or absorb exceptionally loud or intense sounds, and yet collect and concentrate without materially modifying sounds within the usual or predetermined range of intensity.

A further object is to provide a mouthpiece in which no metal, with its corroding and tarnishing tendencies, is used in proximity to the lip-portion of the mouthpiece. The nearest approach to this, heretofore, has been the provision of a glass lip-portion, but these were frequently broken by being struck against the dictating machine, table or floor. Especially is this true in the case of large mouthpieces, because with these the danger of breakage is greater due to the relatively great weight of the entire mouthpiece including the glass lip-portion, which of necessity was made relatively heavy.

All these objects and others hereinafter referred to, are attained by this invention by making the sound collector or mouthpiece relatively large and gradually tapering inwardly, and by using a nitro-cellulose product as the material thereof, which is of such thickness that it will resiliently yield and not break when violently struck against the dictating machine, the desk or the floor. Such material, it has been found, is substantially non-resonant under ordinary conditions, and hence does not appreciably modify the ordinary sound it collects; yet it tends to absorb, because of its yielding nature, some of the harsh and excessively intense sounds, and thus eliminates to a large measure "blasting" of the diaphragm of the dictating machine to which it is connected.

Preferably the material is treated so as to be relatively hard to ignite and so as to have a relatively low rate of burning.

As will hereinafter appear, the present invention also provides for securing the nitro-cellulose sound-collector or mouthpiece to the sound-conveyor or speaking-tube by convenient and positive means. This preferably comprises a metal-

lic ferrule (aluminum is satisfactory) secured by rivets to the sound-collector and adjustably attached to a sound-conveyor by a clamping screw.

Other objects and advantages will hereinafter appear.

In the accompanying drawing, which illustrates the present invention in its preferred form—

Figure 1 is a side elevation of the handle of the sound-conveyor or speaking-tube with the mouthpiece of the present invention attached thereto, a portion of the mouthpiece being broken away to show its construction.

Fig. 2 is a transverse section taken on the line 2—2 of Fig. 1, showing the construction of the nitro-cellulose mouthpiece.

Fig. 3 is a longitudinal section through the lower portion of the mouthpiece, its ferrule and the handle portion of the sound-conveyor or speaking-tube to which it is attached.

As shown in the accompanying drawing, the sound-conveyor or speaking-tube 10 is attached to a handle-portion 11 made of metal, preferably aluminum for lightness, and this handle-portion has a finger guard or guide 12 provided thereon at one side and a manually operable stop-and-start button 13 at the other side. The speaking-tube leads to the dictating machine where the sound which is conveyed is recorded or reproduced while the handle 11 on the other end of the speaking-tube is connected to the mouthpiece 16 in a manner hereinafter described.

As stated above, the mouthpiece, which for the purpose of the present specification is intended to mean all that portion of the sound-collector up to the handle 11, is made large enough at its lip 14 to collect a major portion of the sound emitted by a speaker or dictator while the lip 14 is held at such a distance from the face of the speaker that the sound emitted both through the throat and through the nose is collected. For practical purposes and by way of example, the internal diameter of the lip-portion 14 is preferably about $2\frac{1}{4}$ inches.

From the lip-portion 14, the mouthpiece gradually tapers through its throat portion 16 where it connects with the handle 11 and has substantially the same internal diameter as the handle 11. As shown, the mouthpiece is bent so that the lip 14 lies in a plane at an angle to the axis of the handle 11, so that the handle 11 may be held in a more convenient position by the operator while the lip 14 is substantially parallel with the dictator's face. In order that the taper may be sufficiently gradual, it is necessary that the mouthpiece be rather long, and hence the mouthpiece

is large both in cross-sectional area and in length.

Such a mouthpiece as shown, when made of metal of sufficient rigidity so that it would not vibrate and thus modify the sound being collected, 5 is excessively heavy and its weight is augmented by the provision of a glass lip engaging portion which of necessity is also heavy. While such a metal and glass mouthpiece is practicable and has been used to a considerable extent, nevertheless, it has been found fatiguing to dictators to hold this mouthpiece in speaking position for any considerable length of time.

The present invention, therefore, as stated above, has for its object the provision of an 15 acoustically efficient mouthpiece which is not excessively heavy. In attaining this end, the present invention has provided a mouthpiece made of nitro-cellulose such as pyralin, celluloid or like material which, because of its non-resonant characteristic, may be used much thinner than metal of the same characteristic. Moreover, it has been found that a mouthpiece made of such material, when made sufficiently thin, tends to absorb in the walls of it some of the energy of exceptionally 25 loud or harsh sounds and passes these sounds on to the sound-conveyor in a somewhat modified form. Hence, it materially eliminates blasting of the diaphragm connected with the sound-conductor. Again, it has been found that a mouthpiece 30 of nitro-cellulose or like material when made sufficiently thin is practically unbreakable and thus is a decided improvement over mouthpieces heretofore employed which were provided with a glass lip-engaging portion. The nitro-cellulose mouthpiece resiliently yields instead of cracking when it is brought violently into contact with the 35 dictation machine, desk, floor or other hard objects. It has all the advantages of glass, for its surface is smooth and may easily be cleaned with water, and it has none of the disadvantages of 40 some metals which, due to the moisture deposited upon them (because the mouthpiece is located directly in front of the speaker's mouth) tarnish or corrode.

45 While light materials of various thickness may be employed, yet it is preferable, as shown by actual experiment, to use material ranging from $\frac{1}{2}$ to $\frac{1}{6}$ of an inch in thickness.

Practical tests have also shown that it is preferable 50 that the lip 14 or outer portion of the mouthpiece be made about twice as thick as the main body portion 17, as shown at 15. Hence, for this reason and for the reason that it is more desirable to make the mouthpiece out of sheet pyralin 55 rather than by other methods, the lip-portion 14 is made separate from the body portion 17 and these two portions are united preferably by a lap joint 18 held together by adhesion.

Because it is also preferable to make it out 60 of sheet material, the body portion 17 is also made of two parts, 17a and 17b, and these are united by lap joints 19 secured together by adhesion. These lap joints 19 have the further advantage of 65 strengthening the body portion 17 against collapsing and against bending in the direction of the incline of the mouthpiece.

At its throat end 16, the mouthpiece is preferably riveted or otherwise secured to a metallic ferrule 20, preferably of aluminum, which extends beyond the throat portion 16, so that a part 70 of it can overlie the end of the handle 11 and telescope with it. The mouthpiece and handle when so telescoped are held together by means of a screw 21 passing through a hole 22 in the ferrule and threaded into the handle 11, so that

when the screw is adjusted in place the mouthpiece and the handle will be held firmly together.

In order to permit the mouthpiece to be adjusted about the axis of the handle so that the 85 inclination of the lip-portion 14 may be varied with regard to the manually operable button 13 and the finger guard 12 on the handle, the hole 22 is elongated so as to form a slot allowing movement of the ferrule and mouthpiece with regard to the screw when the screw is loosened. When 95 the screw is tightened, the head thereof holds the ferrule securely in place against rotary or other movements.

Preferably, the lip-portion 14 is beaded over 100 as at 23 to provide a smooth round surface which 90 might be brought into contact with the dictator's face, and which further strengthens and stiffens the mouthpiece.

Variations and modifications may be made within 105 the scope of this invention and portions of the 95 improvements may be used without others.

Having now described the invention, what is claimed as new and for which it is desired to obtain Letters Patent, is:—

1. A sound-collector for dictating machines 100 having a body-portion made of nitro-cellulose, and a lip-portion made of nitro-cellulose of substantially twice the thickness of the nitro-cellulose of the body-portion and secured to said body-portion to form therewith a substantially integral 105 structure.

2. A sound-collector for dictating machines having a body portion comprising two parts of sheet nitro-cellulose secured together side-by-side to form part of a horn-shaped structure; and 110 a lip-portion of sheet nitro-cellulose secured to the said two parts to complete the horn-shaped structure.

3. A sound-collector for dictating machines having a body portion comprising two parts of 115 sheet nitro-cellulose substantially $\frac{1}{2}$ of an inch in thickness, said parts being secured together to form part of a horn-shaped structure; and a lip-portion of sheet nitro-cellulose of substantially $\frac{1}{4}$ of an inch in thickness secured to said two 120 parts to complete the horn-shaped structure.

4. A sound-collector for dictating machines having a body portion comprising a plurality of parts of sheet material secured together side by side to form a horn-shaped structure, and a lip 125 portion of substantially twice the thickness of the body portion secured to the said parts to complete the horn-shaped structure.

5. A sound-collector for dictating machines having a body portion comprising a plurality of 130 parts of sheet nitrocellulose cemented together along their longitudinal edges to form a horn shaped structure, and a nitrocellulose lip portion of substantially greater thickness than said body portion cemented to said body portion along its 135 circumferential overlapping edges.

6. A sound-collector for dictating machines having a body portion comprising a plurality of parts of sheet material secured together side by side to form part of a horn shaped structure, said 140 parts being cemented together along overlapping edges to provide ribs extending longitudinally of the horn shaped structure for stiffening purposes, and a nitrocellulose lip portion of substantially 145 greater thickness than said body portion cemented to said body portion along its circumferential overlapping edges.

7. A sound-collector for dictating machines having a body-portion comprising two parts of sheet nitro-cellulose secured together side-by- 150

side to form part of a horn-shaped structure, a metallic ferrule riveted to the throat of said body-portion for connecting it to a sound-conduit, and a lip-portion of sheet nitro-cellulose secured to 5 the other end of said body-portion to complete the horn-shaped structure.

8. A sound-collector for dictating machines having a body-portion comprising two parts of sheet nitro-cellulose secured together side-by-side 10 to form part of a horn-shaped structure, and a lip-portion of sheet nitro-cellulose of greater thickness than the sheet material of the body-portion and secured to said body-portion to complete the horn-shaped structure.

15 9. A sound collector for dictating machines having a body portion of nitro-cellulose, a lip portion made of nitro-cellulose having a thickness substantially greater than the thickness of

the body portion, said lip portion being secured to said body portion to form therewith a substantially integral structure.

10. A sound collector for dictating machines, including an elongated body portion formed from relatively thin sheet organic material having non-resonant characteristics; a lip portion integrally attached to said body portion to form therewith a substantially integral structure, said lip portion being formed of the same material from which the body portion is formed, but having a thickness substantially greater than the thickness of the body portion to offset any tendency for the upper part of the body portion to vibrate under the influence of the vibrations of sound waves collected thereby.
